Attorney

UNITED STATES PATENT OFFICE.

GEORGE W. KING, OF MARION, OHIO, ASSIGNOR TO THE MARION STEAM SHOVEL COMPANY, OF MARION, OHIO, A CORPORATION OF OHIO.

SPUD FOR DREDGES.

No. 880,079.

Specification of Letters Patent.

Patented Sept. 4, 1906.

Application filed June 2, 1906. Serial No. 319,953.

To all whom it may concern:

Be it known that I, GEORGE W. KING, a citizen of the United States, residing at Marion, in the county of Marion and State of Ohio, have invented certain new and useful Improvements in Spuds for Dredges, of which the following is a specification, reference being had therein to the accompanying drawings.

This invention relates to spuds for dredges, and has for its object to provide an improved construction of the spud and its guiding devices, whereby their strength and durability are increased.

To these ends the invention consists in certain novel features, which I will now proceed to describe and will then particularly point out in the claims.

In the accompanying drawings, Figure 1 is a side elevation of the rear end of a dredge, showing the spuds in position. Fig. 2 is a plan section of the same. Fig. 3 is an enlarged side elevation of one of the spuds detached. Fig. 4 is a front elevation of the same. Fig. 5 is a sectional view of the same, taken on the line *x x* of Fig. 3 and looking in the direction of the arrows; and Fig. 6 is a similar view taken on the line *y y* of Fig. 3 and looking in the direction of the arrows.

In the said drawings, 173 represents the body of the hull and 174 the spuds at the rear of the hull, by means of which the dredge is anchored in position. The body of each spud is in the form of a box-girder, comprising side plates 175 and front and back plates 176, which extend beyond the side plates and are secured thereto by angle-bars 177. Since these spuds are of considerable length, it is desirable to strengthen their middle portion to enable them to resist the transverse strains to which they are subjected, and I therefore provide along the central portion of the interior of the girder a stiffening-plate 178, which is secured to the front and back plates by means of angle-bars 179. By reason of this construction the required stiffness can

be given to the body of the spud while maintaining the uniform dimensions which are necessary to permit it to properly fit and move in the spud-guides. These latter are shown at 180 arranged vertically in pairs at the back of the hull and provided along the margins of their opposite faces with wearing-plates 181. In order to give the spud a proper bearing on these wearing-plates, it is provided with angle-irons 182, secured to the angle-irons 177 by one member and presenting the other member to the corresponding wearing-plate 181, so as to provide a wearing-surface to coöperate therewith without injury or cutting. This does away with the wooden filling heretofore used between the angle-bars 177 for this purpose, which has always proved unsatisfactory.

I wish it to be understood that I do not desire to be limited to the exact details of construction shown and described, for obvious modifications will occur to a person skilled in the art.

Having thus fully described my invention, what I claim as new, and desire to secure by Letters Patent, is—

1. In a dredge of the character described, a spud composed of a box-girder, and a stiffening-plate connecting the front and rear plates thereof along the central portion of the spud, substantially as described.

2. In a dredge of the character described, a hull having spud-guides provided with wearing-plates along the margins of their opposite faces, in combination with a spud consisting of a box-girder with recessed sides, said spud having angle-bars secured thereto and presenting guiding-surfaces to coöperate with the wearing-plates of the guides, substantially as described.

In testimony whereof I affix my signature in presence of two witnesses.

GEORGE W. KING.
